UNITED STATES PATENT OFFICE.

JOHN N. BROWNLEE, OF DETROIT, MICHIGAN.

DESIGN FOR A POLE FOR ELECTRIC WIRES, &c.

SPECIFICATION forming part of Design No. 27,516, dated August 10, 1897.

Application filed March 5, 1897. Serial No. 626,146. Term of patent 7 years.

To all whom it may concern:

Be it known that I, JOHN N. BROWNLEE, a citizen of the United States, residing at Detroit, county of Wayne, State of Michigan, have invented and produced a new and original Design for a Pole to be Used for Electric Wires and many other purposes, of which the following is a specification, reference being had to the accompanying drawings, forming a part thereof.

My invention relates to designs for poles which are to be used for electric wires and many other purposes; and it consists in the shape and configuration that will be more fully described hereinafter.

Figure 1 is a view in perspective showing features of my design. Fig. 2 is a view in side elevation. Fig. 3 is a view in cross-section on line 3 3, Fig. 1.

The leading features of my design consist in a pole of essentially I shape in cross-section, as shown in Fig. 3, tapering from the base toward the top on all sides.

As shown, A is the center piece of the post, which is tapered toward the top. This center piece is flat upon all four of its sides and

tapers on each side from the bottom toward the top.

A' and A² are the two side pieces, also shown tapered toward the top, the side pieces bordering the outer edges of the center piece and projecting to the front and rear therefrom. These side pieces are grooved upon their inner sides and fit over opposite edges of the center piece and taper in width from their lower ends to their upper ones. They project sufficiently far beyond opposite sides of the center piece to form a groove or recess upon opposite sides, as shown in the accompanying drawings.

The pole is shown surmounted by an ornamental top B.

What I claim is—

The design for a pole, substantially as herein shown and described.

In testimony whereof I sign this specification in the presence of two witnesses.

JOHN N. BROWNLEE.
